 In Germany August 1, 1932

23 Claims. (Cl. 236—25)

The present invention relates to gas valves, and more especially to gas valves incorporating a working part such as a diaphragm, bell, piston or the like which is operated by variations of pressure produced in the controlling chamber of the gas valve by an auxiliary gas current, in the path of which controlling valves are arranged which operate in response to the working conditions to be controlled, for instance temperature, pressure, current velocity, height of liquid and so forth. The invention comprises a controlling device operating in response to pressure changes in the consumption pipe, for example, the feed pipe to a burner, or in response to pressure changes in the gas supply pipe whereby the auxiliary current of gas, besides controlling the feed of gas to the burner in dependence on the working conditions to be controlled, also enables the pressure or the quantity of the gas current allowed to pass to the burner to be kept constant.

Several examples of construction of the invention are shown in the accompanying drawings, in which:—

Figure 1 is a view, partly in side elevation and partly in section and largely diagrammatic of a gas valve with a pressure-control arrangement according to the invention.

Figure 2 is a similar view of a gas valve embodying a control device of somewhat different form and mode of operation from that of Fig. 1 but also coming within the present invention.

Figure 3 is a vertical section through a gas valve having a control device or arrangement like that of Fig. 2 but modified in certain mechanical details.

Figure 4 is a plan view of the gas valve shown in Fig. 3 with the casing cover removed.

Fig. 5 is a vertical sectional view of a gas valve identical with that shown in Fig. 3 except for a modification in the means provided for adjusting the control device.

Fig. 6 is a partial vertical sectional view of the valve shown in Fig. 3 but with a further modification in the said adjusting means.

Fig. 7 is a partial vertical sectional view of the valve shown in Fig. 3 but with a still further modification in the said adjusting means.

Figure 8 is a section, and

Figure 9 a plan view of a slightly modified form of the controlling valve forming a part of the Fig. 3 construction.

Referring first to the embodiment of the invention shown in Fig. 1, A denotes generally the gas valve which controls the passage of the main

gas entering at 10 into a burner pipe 11 leading to a main burner B. The valve, denoted generally at A, comprises a casing within which is located the main valve 12, secured to the diaphragm 13, which diaphragm bounds, on the one side, the main pressure chamber 14, and on the other side, the control chamber 15 of the valve casing, and in which latter chamber a closing spring 16 is arranged. The diaphragm 13 is operated by differences in pressure which are produced in the control chamber 15 by the opening and closing of a current of control gas. The current of control gas is derived from the main pressure chamber 14, and flows through a passage 17 first into a distributor chamber 18. The distributor chamber is in permanent communication by a narrow throttle 19 with a control pipe 20, whose outlet 21 is controlled by a thermostatic valve 22 influenced by the pilot flame, which valve is connected with a heat-sensitive expansible diaphragm 23 of a safety pilot burner C. The narrow throttle 19 limits the strength of the current of gas, which is necessary for the permanent maintenance of the pilot flame. Further, the distributor chamber is in permanent communication with the control chamber 15 by a wide throttle 24, which limits the greatest amount of control gas which can flow to the control chamber 15. The control chamber 15 is closed by a partition wall 50 in which an aperture 51 is provided, controlled by a controlling valve 52. The opening 51 connects the control chamber 15 with a chamber 53, through the wall 54 of which the rod 55 of the controlling valve 52 is carried in a gas-tight manner and is connected with the controlling diaphragm 56 of a pressure-controller F, the pressure chamber 57 of which is connected by a passage 58 with the outlet 11 of the gas valve A. The respiratory chamber 59 of the pressure controller F is closed by a cover 60 having an opening 61.

If the consumption pressure rises in the valve outlet 11, this increase in pressure is transmitted through the passage 58 to the chamber 57 of the pressure controller and presses the controlling diaphragm 56 downwards against the action of a loading spring 62, so that the controlling valve 52 is more or less closed. Consequently the current of control gas flowing through the passage 17, distributor chamber 18 and the wide throttle 24 into the control chamber 15 accumulates and causes the valve diaphragm 13 to rise and somewhat close the main valve 12, whereby the pressure in the consumption pipe 11 is again reduced to the adjusted maximum value.

The current of control gas passed by the controlling valve 51, 52 of the pressure controller F flows from the chamber 53 through a passage 25, which opens into a valve chamber 26 of a controller D which responds to variations of any working conditions to be controlled. The controller D might, for example, be a thermostatic valve which responds to the heat of a room or a liquid; it might also be a water-level controller or a steam-pressure controller. The example of construction illustrated shows the gas valve employed in connection with a water-heater or geyser and the controller D comprises a vane or valve operated by the current of water. In the valve chamber 26 of this controller D a controlling valve 27 is arranged, which controls the outlet 28 of the chamber 26 in the control gas pipe 20 and is connected to a lever 29, which is rockably mounted in a diaphragm 30.

The diaphragm 30 forms at the same time a closure for the chamber 31 on the gas side, in which one arm of the rocking lever 29 is situated, against a chamber 32 traversed by the water, into which the other arm of the lever 29 carrying a disc 33 projects. The water chamber 32 is connected, on the one hand, to a water supply pipe 34, and on the other hand to a water pipe 35 leading to the heater E, the outlet of which is controlled by one or more cocks Z.

So long as water is not flowing, the control valve 27 is closed by the overbalancing weight of the disc 33. The control gas can thus flow outwardly from the distributor chamber 18 only through the narrow throttle 19, whilst the admission of the control gas through the passage 17 takes place almost unthrottled. Consequently, there prevails in the distributor chamber 18 almost the main gas pressure, which is transmitted through the wide throttle 24 to the control chamber 15, so that the same pressure prevails on both sides of the diaphragm 13 and the spring 16 holds the valve member 12 of the main gas valve A closed. If, on the other hand the cock Z is opened, the flowing water striking on the disc 33 rocks the lever 29 and opens the control gas valve 27 of the water current controller D. Consequently, the control gas which is in the chamber 15 can flow away unthrottled through the open valve 52, chamber 53, duct 25, chamber 26, and outlet 28 to the control pipe 20, whilst the control gas flowing from the distributor chamber 18 through the throttle 24 is throttled, so that a fall in pressure takes place in the control chamber 15. This fall in pressure effects the opening of the main valve 12, so that now the gas flows to the burner B, where it is ignited by the pilot flame of the pilot burner C. The pressure controller F then causes the pressure in the burner pipe 11 to be kept uniform.

If the pilot flame at the safety pilot burner C goes out for any reason the thermostatic valve 22, 23 closes the outlet of the control gas pipe 20 so that the pressure in the control pipes and in the control chamber 15 rising to the main pressure causes the closing of the main valve 12. The current of control gas thus serves for controlling the main valve in dependence on the safety device C and the water controller D as well as for regulating the consumption pressure of the gas in the outlet pipe 11 leading to the burner.

From the distributor chamber 18 an ignition pipe 63 also leads to the pilot burner C, and serves for by-passing the thermostatic valve 22 and is controlled by manually operated ignition valve 64.

In Figures 2-9 a gas valve is shown, in which the quantity of gas passing through in a unit of time is kept constant instead of the pressure in the outlet pipe of the valve.

In the diagrammatic drawing (Fig. 2), A again generally designates the gas valve, which controls the flow of the main gas from the main supply pipe 110 to a burner pipe 111 leading to the main burner B. The main valve 112 is again connected to the valve-operating diaphragm 113, which however does not directly form a boundary wall of the main gas chamber 114, as in the Fig. 1 construction, but is enclosed in a capsule which is inserted in the casing of the gas valve between the parts 300 and 301 of that casing so as to be changeable. The capsule consists of a partition wall 170, which cooperates with the diaphragm 113 to separate off a control chamber 171 in front of or above the diaphragm and through which passes a valve-rod 172 connecting the main valve 112 with the diaphragm 113, and of a hood 173 which cooperates with the diaphragm to separate off a controlling pressure chamber 115 from an ante-chamber 174 formed by the hood and the lower part 300 of the outer casing of the valve. The hood 173 is formed with a non-return valve casing 175 in its lower wall, which contains a non-return valve 178 having a throttle so controlling 179, said valve opening a passage 176 in the bottom of the valve casing as to open the passage when there is excess pressure in the ante-chamber 174 and closing under the action of a spring 177 on a fall in pressure in the ante-chamber 174. This non-return valve serves for influencing the speed of operation of the gas valve, in that by opening the passage 176 it allows any rise in pressure in the ante-chamber 174 to quickly enter the controlling chamber 115, so that the diaphragm 113 rapidly closes the main valve 112, whilst on a fall in pressure in the ante-chamber 174 it closes the passage 176, and allows the controlling pressure acting on the valve diaphragm 113 to escape only slowly through the throttle opening 179, so that the main valve 112 only slowly opens.

The partition wall 170 carries a cup 180, which closely surrounds the outlet 111, so that the seat of the main valve 112 and the main valve 112 with its closing spring 116 are situated within the intermediate pressure chamber 181 enclosed by the cup 180 and the partition wall 170. The wall of the cup 180 is provided with openings 182, which can be more or less opened or closed by means of a sliding valve 183 or the like. These openings 182 by their throttling action enable a difference in pressure to be produced between the high pressure in the main pressure chamber 114 and the intermediate pressure in the chamber 181 within the cup 180. This difference of pressure is used to operate a controlling member which controls the control gas pressure acting on the diaphragm 113. For this purpose, an opening 184 is provided in the cup 180 leading into a chamber 185, in which a pressure-sensitive controlling member, which may be a diaphragm, piston, bell, float or the like, but in the present instance is a controlling disc 186, is so arranged that the main pressure prevailing in the main pressure chamber 114 acts on one side of it, and on its other side the intermediate pressure in the chamber 181. The controlling disc so slidably fits the chamber 185 that the disc is moved by the difference between these two pressures. A spring 187 opposes the higher pressure. The controlling disc 186 is so arranged that it governs the inlet to a passage 75

188 which leads from the intermediate pressure chamber 181 into the controlling pressure chamber 171 in front of (above) the valve-operating diaphragm 113.

5 The current of control gas flowing from the intermediate pressure chamber 181 through the passage 188 into the controlling chamber 171 in front of or above the diaphragm 113 passes through a passage 117 into a distributor chamber 118, which is in constant communication by a narrow throttle 119 with a control gas pipe 120 terminating in a thermostatic safety pilot burner C, whose function is the same as that of the pilot burner C described with reference to Fig. 1. A second but wide throttle 124 connects the distributor chamber with a passage 125, which leads at one side into the ante-chamber 174 behind or below the diaphragm 113 and on the other side into the valve chamber 126 of a controller D. For the sake of simplicity, the control arrangement is again shown in the same way as in Fig. 1, so that it is needless to describe it.

The mode of working of the gas valve shown in Fig. 2 is as follows:—

25 When no water is flowing through the pipe 134, 135, the controlling valve 127 remains closed. The control gas flows from the intermediate pressure chamber 181 through the passage 188 into the control chamber 171 above the diaphragm 113 and then passes from the chamber 171 through the passage 117, distributor chamber 118 and the wide throttle 124 to the passage 125 and from there into the ante-chamber 174. The non-return valve 178 opens and allows the control gas 30 to enter the chamber 115 directly behind the diaphragm 113. Substantially the same pressure now prevails on both sides of the diaphragm 113, and therefore the force of the closing spring 116 can press the valve plate 112 on to its seat. A 35 very small quantity of gas flows continuously through the narrow throttle 119 to the pilot burner C and there maintains a pilot flame. When the controlling valve 127 is opened by the pressure of the flowing water, the gas escapes 40 from the ante-chamber 174 very rapidly through the unthrottled outlet 128 into the control gas-pipe 120. On the other hand, the control gas enclosed in the control chamber 115 can flow only slowly through the fine opening 179 in the non-return valve 128 into the ante-chamber 174. As 45 the throttle 124 is narrower than the outlet 128 of the control pipe 120 and only allows the passage of a limited quantity of control gas, there arises in the ante-chamber 174 and in the control chamber 115 behind the diaphragm 113 a 50 drop in pressure relative to the pressure of the gas in the control chamber 171 on the front side of the diaphragm, which effects the opening of the valve 112. The opening is however completed only slowly, because the non-return valve 178 55 closes, and the passage of the gas from the control chamber 115 to the ante-chamber 174 is possible only through the fine opening 179. The gas coming from the main gas-pipe 110 flows through the opening 182 in the partition wall 180 before it passes into the burner pipe 111. The effective cross-section of the gas-passage is adjusted by the slide or valve 183 corresponding to the gas consumption of the main burner B. If the gas consumption of a burner is small, the openings 182 in the wall 180 are suitably closed by moving the valve 183; if the gas consumption of the apparatus for which the gas controlling valve is intended is large, the openings 182 are further opened. This adjustment corresponds, however,

only for a given pressure of the gas mains. In order even where the mains pressure is variable, to enable a uniform quantity of gas to be constantly supplied to the burner B, the valve plate 112 must narrow the gas passage when the mains pressure is higher and enlarge it when the mains pressure is smaller. The controlling disc 186 is employed for this purpose. A fall in pressure occurring in the gas current through the valve casing between the main pressure chamber 114 and the chamber 181 enclosed by the partition wall 180, influences the controlling disc 186 and thus the current of control gas which flows through the opening 188. If the mains pressure increases, the controlling disc 186 is forced towards the opening 188. As the control gas further flows away through the passage 117, the pressure is reduced in the control chamber 171 directly above or in front of the diaphragm 113. Consequently, the valve plate 112, under the influence of the 20 spring 116, can now execute a closing movement, and the cross-section of the gas passage is reduced. If the pressure difference between the chambers 114 and 181 is reduced to a value equal to or less than the force of the spring 187, the controlling disc 186 is brought by the spring 187 again into the initial position. The throttling action thus ceases and the pressure in the control chamber 171 above the diaphragm 113 again increases, so that the gas control valve 112 is correspondingly further opened. The varying pressure of the mains is thus regulated by the controlling disc 186 automatically for the passage of a constant quantity.

In the gas valve according to Figs. 3 and 4, the upper boundary wall 180 of the diaphragm capsule 170, 173 is provided with sector-shaped recesses 189 which open towards the intermediate pressure chamber 181 and are closed at top by the revolute adjusting valve ring 183. The adjusting valve ring 183 corresponds at the same time to the partition wall 180 of Fig. 2, as it separates the main pressure chamber 114 from the intermediate pressure chamber 181. It is provided with a scale 190 according to which the 45 adjustment for the desired gas quantity takes place. The adjustment of the valve ring 183 is effected by rotation about the axis of the gas valve, it being guided by wall parts 191. A screw 192 serves for clamping the valve ring 183 in adjusted position. The openings 182 are so arranged in the valve ring 183, and of such shape, that in dividing the scale into equal parts each rotation of the valve ring by one division always corresponds to a variation of the gas quantity by 50 the same amount. The controlling disc 186 of the controller for the gas quantity is mounted in a cup-shaped casing or capsule 193 screwed into the boundary wall 170. A sieve 194 retains any impurities in the gas above the main valve 112; furthermore, in front of the controlling disc 186 a fine-mesh sieve 195 is also arranged and connected with the controlling capsule 193, and prevents even the finest impurities from reaching 55 the controlling disc 186.

Figs. 5-7 show devices operable from the outside for the adjustment of the valve ring 183, so that the casing of the gas valve need not be opened up for adjustment of the quantity of gas. 70 For this purpose, the valve ring 183 in Fig. 5 is provided with a toothed portion 196, in which engages a toothed wheel 198 on a small shaft 197. The toothed wheel 198 can be rotated, as required, by means of the head 199 provided with 75

an adjustment scale and thus the valve ring 183 can be adjusted.

The arrangement according to Fig. 6 differs from that in Fig. 5 only by the fact that the shaft 197 of the pinion 198 is separate from the adjusting knob 199, which is only inserted like a key or spanner when an adjustment is to be made. The adjusting gear wheel 198 is of such smaller diameter than the shaft 197, that the shaft 197 with the gear wheel 198, can be entirely removed after the adjustment is made, and the opening of the passage for the shaft bearing closed by a plug. By this means an unauthorized adjustment of the valve ring 183 is obviated. According to Fig. 7 by adjusting a screw 200, a plate 201 can be moved relatively to an additional passage 202 leading laterally from the main pressure chamber 114 to the intermediate pressure chamber 181, and the said passage is thereby more or less opened, whereby the quantity of gas flowing through the valve and the difference in pressure prevailing on the controlling disc 186 are varied. The screw 200 is accessible from the outside by an opening 203 which can be closed. The controlling disc capsule consists according to Figs. 8 and 9 of a cup-shaped casing or capsule 193, which is provided with a threaded stem 204, and a cover 205 in which the sieve 195 is clamped. The cover 205 has openings 206 for the passage of the gas from the main pressure chamber 114, whilst the bottom of the capsule 193 has openings 207 for the entrance of the gas from the intermediate pressure chamber 181. The controlling disc 186 is inserted so as to lie free in the capsule 193, 205. The controlling spring 187 is introduced into an annular recess 208 in the stem 204. The disc 186 is provided with projections 209, to ensure that the disc does not bear with its whole surface, but only at points, against the walls of the capsule. By this means any sticking of the disc is prevented. The capsule 193 with its contained parts of the Fig. 8 construction is a modification of the capsule 193 and its contained parts of the Fig. 3 construction and is intended to be mounted in one of the recesses 189 of the intermediate-pressure chamber 181 as shown for the capsule 193 in the Fig. 3 construction and the passage 188 through the stem of the capsule 193 of Fig. 8 forms the inlet for the controlling gas from the intermediate-pressure chamber 181 to the control pressure chamber 171 in front of or above the diaphragm 113 (see Fig. 2). If the difference in pressure on the opposite sides of the disc 186 is smaller than the force of the spring 187, the disc is raised from its seat 210 by the spring 187, and the control gas from the intermediate pressure chamber 181 can pass through the openings 207 into the capsule 193 beneath the disc 186 therein and therefrom through the passage 188 into the control chamber 171 directly above the diaphragm 113. If the difference in pressure is greater than the force of the spring, the current of control gas is throttled by the controlling disc 186 which is moved against the valve-seat 210. In order that the unavoidable inexactitudes in manufacture of the controlling devices may be compensated for, a pivoted valve plate 211 is provided in the cover of the capsule 193 above the openings 206, and by turning this pivoted valve plate the width of passage of the openings 206 and thus the fall in pressure can be varied.

We declare, that what we claim is:

1. A diaphragm-operated gas valve comprising a main casing having a gas inlet and a gas outlet

at one end thereof, a main division plate in said casing having a control passage therethrough, a main diaphragm on the side of said division plate opposite said gas inlet and gas outlet, a main valve on the other side of said division plate controlling said outlet, a connection between the diaphragm and the valve, a shroud enclosing said main valve and the outlet opening and having a valve-controlled opening therein, a valve member within said shroud and subject to the pressures on opposite sides of the shroud for controlling said control passage and for influencing the diaphragm to maintain substantially constant the volumetric flow through said outlet and a controller subject to external working conditions connected with opposite sides of said main diaphragm.

2. A diaphragm-operated gas valve comprising a casing having a gas inlet and a gas outlet at one end thereof, a main division plate in said casing having a control passage therethrough, a main diaphragm on the side of said division plate opposite said gas inlet and gas outlet, a main valve on the other side of said division plate controlling said outlet, a connection between the diaphragm and the valve, a shroud enclosing said main valve and the outlet opening and having a controllable opening therein, a valve member consisting of a thin disc within said shroud and subject to the pressures on opposite sides of the shroud for controlling said control passage and for influencing the diaphragm to maintain substantially constant the volumetric flow through said outlet and a controller subject to external working conditions connected with opposite sides of said main diaphragm.

3. A gas valve according to claim 1 and comprising a spring operating on said valve member against the gas pressure on the outer side of said shroud and a capsule removably mounted in said shroud and containing said valve member and spring.

4. A gas valve according to claim 1 and further characterized by a capsule removably mounted in said shroud, said valve member being mounted in said capsule and a spring disposed between the base of said capsule and said valve member, and said valve member having projections thereon in order to reduce the area of its contact with the base surface of said capsule.

5. A gas valve according to claim 1 and comprising a double-walled casing member inset in said main casing enclosing said diaphragm, one wall of said casing member constituting said main division plate and having an opening there-in forming said control passage, a capsule having a base provided with a bored stem removably mounted in said shroud to dispose said stem in said opening and a control valve in said capsule adapted to control said opening in the division plate.

6. A diaphragm-operated gas valve comprising a main casing having a gas inlet and a gas outlet at one end thereof, a main division plate in said casing having a control passage therethrough, a main diaphragm on the side of the division plate opposite said gas inlet and said gas outlet, a main valve on the other side of said division plate controlling said outlet, a connection between the diaphragm and the valve, a shroud enclosing said main valve and the outlet opening and having an opening therein, a manually adjustable valve member controlling said opening in said shroud and thereby governing the pressure difference on opposite sides of said shroud.

a valve chamber in said shroud disposed over said control passage and removed from said opening in said shroud, a valve member within said chamber intermediate its top and bottom, said chamber having an opening at its top through said shroud and an opening in its bottom communicating with said control passage through said main division plate and with the interior of said shroud so as to subject said valve member to the pressures on opposite sides of the shroud for controlling said control passage and for influencing the diaphragm to maintain substantially constant the volumetric flow through said outlet, gas-conduit means connecting opposite sides of said diaphragm, and a pressure-relief valve having a controller member subject to external working conditions connected with the side of said main diaphragm opposite said main division plate. 5

7. A gas valve according to claim 6 and comprising a toothed ring on said manually adjustable valve member, a toothed wheel engaging said ring and a spindle connected to the wheel for manually adjusting said valve member. 10

8. A gas valve according to claim 1 further comprising a slide valve member as the valve for said opening in the shroud and a set screw for adjustment of said slide valve member accessible through an opening in the valve casing and a removable plug for closing said opening in the valve casing. 15

9. A diaphragm-operated gas valve comprising a casing having a gas inlet and a gas outlet at one end thereof, a main division plate in said casing having a control passage therethrough, a main diaphragm on the side of said division plate opposite said inlet and outlet openings, a main valve on the other side of said division plate controlling said outlet, a connection between the diaphragm and the valve, a shroud enclosing said main valve and the outlet opening and having a valve-controlled opening therein, a valve member within said shroud and subject to the pressures on opposite sides of the shroud for controlling said control passage and for influencing the diaphragm to maintain substantially constant the volumetric flow through said outlet, a gas conduit connecting the opposite sides of the diaphragm for the flow of gas from the side of said diaphragm facing said main division plate to the opposite side of said diaphragm, a throttling restriction interposed in said gas conduit, a pressure-relief valve connected to said gas conduit on the outflow side of said throttling restriction and a controller member for said pressure-relief valve subject to external working conditions. 30

10. A gas heating plant and control system therefor comprising a container of a fluid medium to be heated having a supply inlet and a discharge outlet, a main gas burner, a gas supply for said burner, a main gas valve having an inlet side connected to said gas supply and an outlet side connected to said main gas burner, means comprising a diaphragm so controlling said main gas valve as to maintain said valve in closed position when the gas pressures are approximately the same on opposite faces of the diaphragm and operable by differences in gas pressure on the opposite faces of said diaphragm to effect degrees of opening movement of said main gas valve corresponding to differences in gas pressure on opposite faces of said diaphragm, conduit means fed with gas from said gas supply and connected to opposite sides of said diaphragm and a control valve connected with said control-gas conduit and operating in response to changes in the working conditions of said fluid medium in the plant to control the time of opening and closing of said main gas valve, and additional control-means comprising a valve connected with said control-gas conduit and actuated by the main gas flow when said main gas valve is open to so control the differential pressures on said diaphragm and thereby the extent of opening of said main gas valve as to maintain the flow of gas to said main gas burner substantially at a volumetric constant. 35

pressure-control valve connected with said conduit means and operating in response to changes in the working conditions of said fluid medium in the plant to determine the time of opening and closing of said main gas valve, and means operating in response to variations in pressure in the main gas flow when said main gas valve is open to so vary the differential pressures on said diaphragm as to decrease the extent of opening movement of said main gas valve upon increase in pressure in the main gas flow above a predetermined pressure and to increase the extent of opening movement of said main gas valve upon decrease in pressure in the main gas flow below said predetermined pressure. 15

11. A gas heating plant and control system therefor comprising a container of a fluid medium to be heated having a supply inlet and a discharge outlet, a main gas burner, a main gas pipe, a valve casing having an inlet connected to said pipe and an outlet passage connected to said main gas burner, a main gas valve for said outlet passage, means comprising a diaphragm so controlling said main gas valve as to maintain said valve in closed position when the gas pressures are approximately the same on opposite faces of said diaphragm and operable by differences in gas pressure on the opposite faces of said diaphragm to effect degrees of opening movement of said main gas valve corresponding to differences in gas pressure on opposite faces of said diaphragm, conduit means fed with gas from said main gas pipe and connected to opposite sides of said diaphragm to produce gas pressures thereagainst, a gas-pressure-control valve connected with said conduit means and operating in response to changes in the working conditions of said fluid medium in the plant to determine the time of opening and closing of said main gas valve, and means so operating in response to variations in the gas pressure in said outlet passage on the outlet side of said main gas valve when said main gas valve has been opened by said gas-pressure-control valve as to decrease the extent of opening movement of said main gas valve upon increase in gas pressure in said outlet passage above a predetermined pressure and to increase the extent of opening movement of said main gas valve upon decrease in gas pressure in said outlet passage below a predetermined pressure. 40

12. A gas heating plant and control system therefor comprising a container of a fluid medium to be heated having a supply inlet and a discharge outlet, a main gas burner, a gas supply for said burner, a diaphragm-operated main gas valve for said gas supply having a diaphragm adapted to be actuated by differential pressures, means comprising a control-gas conduit supplied with gas from said gas supply and connected to opposite sides of said diaphragm and a control valve connected with said control-gas conduit and operating in response to changes in the working conditions of said fluid medium in the plant to control the time of opening and closing of said main gas valve, and additional control-means comprising a valve connected with said control-gas conduit and actuated by the main gas flow when said main gas valve is open to so control the differential pressures on said diaphragm and thereby the extent of opening of said main gas valve as to maintain the flow of gas to said main gas burner substantially at a volumetric constant. 45

13. A gas heating plant and control system therefor comprising a container of a fluid medium to be heated having a supply inlet and a discharge outlet, a main gas burner, a main gas pipe, a valve casing having an inlet connected to said pipe and an outlet passage connected to said main gas burner, a diaphragm-operated main gas valve for said outlet passage having a diaphragm adapted to be actuated by differential pressures, means comprising a control-gas conduit supplied with gas from said main gas pipe and connected to opposite sides of said diaphragm and a control valve connected with said control-gas conduit and operating in response to changes in the working conditions of said fluid medium in the plant to control the time of opening and closing of said main gas valve and additional control means comprising a pressure-controlled valve connected to one side of said diaphragm and having a pressure-controlled member exposed to and actuated by the gas pressure in said outlet passage on the outlet side of said main gas valve to so control the differential pressures on said diaphragm and thereby the extent of opening of said main gas valve as to maintain the gas pressure in said outlet passage on the outlet side of said valve substantially constant.
14. A regulator for the gas supply to a hot water device comprising a main gas burner, a gas supply for said burner, a valve-controlled water pipe, a diaphragm-controlled main gas valve for said gas supply having a diaphragm element operable by differences in gas pressure on its opposite faces to effect degrees of opening movement of said valve corresponding to differences in gas pressure on opposite faces of said diaphragm element, conduit means fed with gas from said gas supply and connected to opposite sides of said diaphragm element to produce gas pressures thereon, a control valve connected with said conduit means and operable by flow of water in said water pipe to establish a difference in gas pressure on opposite faces of said diaphragm element effective in opening said main gas valve and an additional control valve connected with said conduit means and actuated by the main gas flow when said main gas valve is open to so control the differential pressures on said diaphragm element as to maintain the flow of gas to said main gas burner substantially at a volumetric constant.
15. A diaphragm-operated gas valve comprising a main gas supply conduit, a main gas valve for said conduit and a diaphragm mechanically connected thereto and adapted to be actuated by differential pressures on its opposite sides to open said main gas valve, said main gas valve closing when the pressures are substantially equalized on opposite sides of said diaphragm, means comprising a control-gas conduit fed with gas from said main gas supply conduit and connecting opposite sides of said diaphragm and a thermostatically controlled pilot-lighter valve connected to said control-gas conduit automatically operating to establish substantially equal gas pressures on opposite sides of said diaphragm so as to cause said main gas valve to close when said pilot-lighter valve is closed and to establish differential pressures on said diaphragm when said pilot valve is open so as to cause said diaphragm to open said main-gas valve, and means comprising a pressure actuated valve connected with said control-gas conduit and actuated by the main gas flow when said main gas valve is open to so control the differential pressures on said diaphragm and thereby the extent of opening of said main-gas valve as

to maintain the flow of gas through said main-gas valve substantially at a volumetric constant.

16. A diaphragm-operated valve for a gas burner comprising the combination with a main gas burner and a gas supply, of a main gas valve between said supply and said burner, a diaphragm mechanically connected to said valve and adapted to be actuated by differential pressure thereon to open said valve, means comprising a control-gas conduit connecting opposite sides of said diaphragm and fed with gas from said gas supply and a pilot-lighter valve connected to said control-gas conduit automatically operating to establish such gas pressures on opposite faces of said diaphragm as to close said main gas valve when the pilot flame is extinguished, and means comprising a pressure-actuated valve exposed to and actuated by the main gas flow on the supply side of said gas-control conduit and connected with said conduit in series with said lighter-burner valve between the latter and said gas supply and automatically operating in response to changes in pressure of said main gas flow when said main gas valve is open to so control the differential pressures on said diaphragm and thereby the extent of opening of said main gas valve as to maintain the flow of gas through said main gas valve substantially at a volumetric constant.

17. A gas heating plant and control system therefor comprising a container of a fluid medium to be heated having a supply inlet and a discharge outlet, a gas supply, a main gas burner, a diaphragm-operated gas valve between said gas supply and said main burner having a diaphragm adapted to be actuated by differential pressures on its opposite faces to open said main gas valve, gas-conduit-means connecting opposite sides of said diaphragm and fed with gas from said gas supply, a pilot burner connected to said gas-conduit-means and a pilot-lighter valve closing when the pilot flame is extinguished and establishing through said gas-conduit-means such pressures on said diaphragm as to close said main gas valve, a controller valve connected to said gas-conduit-means in series with said pilot-lighter valve, actuating mechanism for said controller valve automatically operating to open and close said controller valve in response to changes in the working conditions of said fluid medium in the plant when said pilot-lighter valve is open and thereby to establish through said gas-conduit means such pressures on said diaphragm as to control the time of opening and closing of said main gas valve, and additional control means comprising a valve connected to said gas-conduit-means in series with said pilot-lighter valve and said controller valve and actuated by the main gas flow when said main gas valve is open to so control the differential pressures on said diaphragm as to maintain the main gas flow through said main gas valve substantially at a volumetric constant.

18. A diaphragm-operated gas valve comprising a main-valve casing having a gas inlet and a gas outlet, a main gas valve in said casing controlling the connection between said inlet and said outlet, a diaphragm casing and a diaphragm therein dividing said diaphragm casing into chambers on opposite sides of the diaphragm, a connection between said diaphragm and said main gas valve whereby said diaphragm operates by differential pressures on its opposite faces to open said main gas valve and said main gas valve closes when the pressures are approximately equalized in said chambers on opposite

- sides of said diaphragm, conduit means connecting one of said chambers with said main-valve casing so as to feed gas from said main-valve casing to said one chamber, conduit means connecting said one chamber with the other of said chambers on the opposite side of said diaphragm for the flow of gas from said one chamber to said other chamber, a pressure-relief valve connected to said other chamber and functioning in the open position to produce a differential pressure in said chambers on the opposite faces of said diaphragm effective in opening said main-gas valve, and a valve in said main-valve casing separate from said main-gas valve automatically operating under the pressure of the main gas flow in said main-valve casing when said main-gas valve is open to so control the feed of gas into said one chamber on one side of said diaphragm and thereby the differential pressures on said diaphragm and the extent of opening movement of said main-gas valve as to maintain the gas flow through said main-gas valve substantially at a volumetric constant.
19. A diaphragm-operated gas valve comprising a casing and a diaphragm therein, said casing being formed with interior walls cooperating with said diaphragm to form chambers on opposite sides of said diaphragm with said diaphragm as the common wall between them, a main-gas inlet to and a main-gas outlet from said casing on one side of said diaphragm, a main-gas valve for said outlet operatively connected to said diaphragm, said diaphragm operating by differential pressures on its opposite faces to open said main-gas valve and said main-gas valve automatically closing when the pressures are approximately the same on the opposite faces of said diaphragm, one of said chambers being connected to said main-gas inlet for feeding gas to said one chamber, conduit means connecting said one chamber with the other of said chambers on the opposite side of said diaphragm for the flow of gas from said one chamber to said other chamber, a pressure-relief valve connected to said other chamber and functioning in the open position to produce differential pressure on the opposite faces of said diaphragm effective in opening said main-gas valve, a pressure-control valve in the connection between said pressure-relief valve and said other chamber and means for operating said pressure-control valve comprising a pressure-operated member subject to the gas pressure in said gas outlet and automatically operating in response to changes in said gas pressure above and below a predetermined pressure.
20. A diaphragm-operated gas valve comprising a casing having a main gas inlet opening and a main gas outlet opening, a main gas valve controlling said outlet opening, a diaphragm in said casing adapted to be operated by differential pressures on its opposite sides, said diaphragm having one side exposed to the pressure of the main gas entering said main gas inlet so as to function as the high-pressure side, and wall means in said casing forming with said diaphragm a pressure-control chamber on the opposite or low-pressure side of said diaphragm, said diaphragm being connected with the main valve to cause displacement of the same, a thermostatic pilot lighter valve automatically closing when the lighter flame is extinguished, a conduit connecting the lighter valve with the high pressure side of said diaphragm, a conduit connecting the lighter valve with the low pressure side of said diaphragm, and a controller valve arranged in the conduit connecting the lighter valve with the low pressure side of said diaphragm and means for operating said controller valve comprising an actuating member influenced by the gas pressure flowing through said outlet opening for influencing the diaphragm and main gas valve to maintain substantially constant the gas pressure in said outlet opening.
21. A diaphragm-operated gas valve comprising a casing having a main gas inlet opening and a main gas outlet opening, a main gas valve controlling said outlet opening, a diaphragm in said casing adapted to be operated by differential pressures on its opposite sides, and wall means in said casing forming with said diaphragm pressure chambers on the opposite sides of said diaphragm functioning as high and low-pressure sides, said diaphragm being connected with the main valve to cause displacement of the same, a thermostatic pilot lighter valve adapted to close when the lighter flame is extinguished, a conduit connecting the lighter valve with the high pressure side of said diaphragm, a conduit connecting the lighter valve with the low pressure side of said diaphragm, conduit means feeding gas from said main gas inlet to the high pressure side of said diaphragm and a controller valve for said conduit means actuated by the main gas flow in said casing when said main gas valve is open to influence said diaphragm and thereby the main valve to maintain substantially constant the volumetric rate of gas flow through said outlet opening.
22. A gas valve according to claim 20 and further characterized by said actuating member comprising an auxiliary diaphragm connected to said controller valve and subject on one side to the gas pressure on the outlet side of the main gas valve.
23. A gas valve according to claim 20 and in which said actuating member comprises an auxiliary diaphragm connected to said controller valve and subject on one side to the gas pressure on the outlet side of said main gas valve and subject on its other side to atmospheric pressure and the action of a spring.
